UNITED STATES PATENT OFFICE.

ARGYLE CAMPBELL, OF CHICAGO, ILLINOIS, ASSIGNOR TO ENTERPRISE RAILWAY EQUIPMENT COMPANY, OF CHICAGO, ILLINOIS.

DUMP-CAR.

1,117,781.

Specification of Letters Patent. Patented Nov. 17, 1914.

Original application filed December 6, 1911, Serial No. 664,291. Divided and this application filed September 13, 1912. Serial No. 720,149.

To all whom it may concern:

Be it known that I, ARGYLE CAMPBELL, a citizen of the United States, residing at Chicago, in the county of Cook and State 5 of Illinois, have invented a certain new and useful Improvement in Dump-Cars, of which the following is a full, clear, concise, and exact description, reference being had to the accompanying drawings, forming a 10 part of this specification.

My invention relates to railway cars, and has for its object the provision of a car of novel design, the novel features relating more particularly to the underframing of 15 the car.

This application is a division of my application Serial No. 664,291, filed Dec. 6, 1911. In my aforesaid co-pending application I set forth a car of a structure which includes the novel features claimed herein, but confine my claims in said fundamental application to a certain hopper construction.

One of the principal objects of my invention is to provide a car of great strength 25 which may be built comparatively cheap and of light construction, the car being especially designed to withstand severe shocks of service.

In describing the invention herein, I will 30 lay particular stress on the features claimed herein; referring however incidentally to the remaining structural features of the car in order to outline the entire construction.

It will, of course, be apparent that the invention herein outlined is capable of application in various ways and while particularly described herein in connection with a car ordinarily known as a ballast car, the invention or certain features thereof are 35 equally applicable otherwise.

Referring to the drawings, Figure 1 is a plan view showing the draft sills, a portion of a single center sill and of a body bolster, and the method of uniting the same; Fig. 2 45 is an elevation partially in vertical section along the line 2, 2 of Fig. 1, showing the draft sills, single center sill, bolster and surrounding parts. Fig. 3 is a cross-sectional view of single center sill taken on line 3—3 50 of Fig. 1; Fig. 4 is a side elevation of a portion of the single center sill showing recess for king pin; Fig. 5 is a cross section of the draft sills taken through line 5—5 of Fig. 2; Fig. 6 is a cross-sectional view on line 6—6

of Fig. 1, and Fig. 7 is a cross-sectional view 55 on line 7—7 of Fig. 2.

In the drawings the numeral 29 represents a single center sill extending longitudinally of the car with its ends passing preferably to the forward edges of the body bolster 30 60 of the car, though the same may be extended to the draft devices, and having a vertical recess 31 on its under surface for the reception of the king pin not shown in the drawings. The said center sill 29 is provided on 65 either side with angle irons 32 secured thereto by means of rivets 33, and preferably attached to the web of said center sill along the line of draft from the draft devices of the car for better distributing the shocks received therefrom.

The numeral 34 represents draft sills extending from the end of the car, preferably to the rear edge of the body bolsters 30, each of the same at either end 75 of the car passing outside of and beyond the end of the center sill 29, and supporting between them suitable draft devices not shown in drawings. The said draft sills are preferably turned inwardly and joined together at their upper edges, as shown in Fig. 5. The spaces between the said center sill and the draft sills are filled by filler blocks 12, 35. In preferable construction four filler blocks are used, two, preferably 80 castings 12, being placed in the space between the sills at the rear of the central line of the transverse body bolster, and two similar filler blocks, preferably castings 35, are placed within the similar spaces in 85 front of the central line of the said body bolster 30.

The numeral 13 designates the end floor of a railway car. The said filler blocks are secured by means of rivets 36 to the center sill 95 29, the draft sills 34 and the top and bottom bolster cover plates 37 and 38 respectively, thus forming a secure binder for the draft sills, single center sill and body bolster, and enabling the transmission of heavy shocks 100 through the same without danger of shearing or buckling. By thus extending the center sill to or beyond the forward edge of the body bolster, and thus binding the same to the draft sills and adjacent parts I am enabled to more than compensate in strength 105 for the recess 31 in the said center sill for the reception of the king pin, and secure a

strong continuous girder in the underframe work of the car body from one end to the other thereof.

From what has thus been described, the application of my invention, of course, to cars will be readily apparent and its nature understood.

As before stated my invention is capable of many modifications, and having thus described one specific form which my invention may take,

What I claim as new and desire to secure by Letters Patent is:

1. The combination of a car body having a single center sill extending at each end beyond the central line of the body bolster, body bolsters a pair of draft sills at each end of the car body the said draft sills extending from the end of the car to the rear edge of the adjacent body bolster, the said center sill and draft sills being suitably bound together by filler blocks into a continuous girder from end to end of the car body, the said center sill being provided near each end with a recess for the reception of a king pin.

2. In a single center sill car a center sill extending at each end thereof to the outer edge of the body bolster, body bolsters and draft sills extending to the inner edge of the body bolsters, and filler blocks secured at each of the meeting points of bolsters, draft sills and center sills, and tying the same together, the said center sill being provided with angle irons on either side thereof along the line of draft, and also provided near each of its ends with a recess for the reception of a king bolt.

3. In a car body an underframe comprising body bolsters, suitable end sills, a pair of draft sills at each end, filler blocks and a single center sill, each of said pairs of draft sills being turned together and joined at the upper edges thereof and fastened to the center sill by said filler blocks.

4. In a car body an underframe comprising

body bolsters, suitable end sills, a pair of draft sills at each end, filler blocks and a single center sill, each of said pairs of draft sills being turned together and joined at the upper edges thereof and fastened to the center sill by said filler blocks, said center sill being provided with recesses in its under surface for the reception of king pins.

5. In a car body an underframe comprising body bolsters, suitable end sills, a pair of draft sills at each end, filler blocks, and a single center sill, each of said pairs of draft sills being turned together and joined at the upper edges thereof, and fastened to the center sill through the filler blocks, the said center sill having recesses for the reception of king pins, and provided back of the body bolsters with longitudinally arranged angle irons.

6. In a car body an underframe comprising body bolsters, suitable end sills, a pair of draft sills at each end, filler blocks and a single center sill, each of said pairs of draft sills being turned together and united at the upper edges thereof and fastened to the center sill along the central line of the said union adjoining the said center sill, the said draft sills being also fastened to the body bolsters the said filler blocks being riveted to the bolster, center sill and draft sills substantially as specified.

7. In a car body an underframe comprising body bolsters, suitable end sills, a pair of draft sills at each end, filler blocks and a single center sill, each of said pairs of draft sills being turned together and joined at the upper edges thereof and fastened to the center sill by said filler blocks, and also fastened to the said center sill along the adjoining length of union of said draft sills, the said draft sills being further fastened to the body bolster substantially as specified.

ARGYLE CAMPBELL.
